(45) Date of Patent: ** Feb. 13, 2024

(54) **BARK CONTROL COLLAR DEVICE**

(71) Applicant: **Shenzhen kersonic Intelligent Technology Co., Ltd.**, Shenzhen (CN)

(72) Inventor: **Yongkai Zhou**, Shenzhen (CN)

(73) Assignee: **Shenzhen kersonic Intelligent Technology Co., Ltd.**, Shenzhen (CN)

(**) Term: **15 Years**

(21) Appl. No.: **29/838,619**

(22) Filed: **May 13, 2022**

(51) LOC (14) Cl. 30-99

(57) **CLAIM**

The ornamental design for a bark control collar device, as shown and described.

DESCRIPTION

FIG. 1 is a perspective view of a bark control collar device, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.
